INVENTOR:

J. M. Duncan
BY *Mann & Co.*

ATTORNEYS.

UNITED STATES PATENT OFFICE.

JOSEPH M. DUNCAN, OF WARSAW, NEW YORK.

EVAPORATOR.

SPECIFICATION forming part of Letters Patent No. 284,952, dated September 11, 1883.

Application filed June 18, 1883. (No model.)

To all whom it may concern:

Be it known that I, JOSEPH M. DUNCAN, of Warsaw, in the county of Wyoming and State of New York, have invented a new and useful Improvement in Evaporators, of which the following is a full, clear, and exact description.

Reference is to be had to the accompanying drawings, forming a part of this specification, in which similar letters of reference indicate corresponding parts in all the figures.

Figure 1 is a plan view of an evaporator, part of the pan being broken away. Fig. 2 is a sectional elevation of the upper part of the partition-wall of the furnace, taken through the line *x x*, Fig. 1. Figs. 3, 4, and 5 are the same section as Fig. 2, but showing modifications of the improvement.

The object of this invention is to prevent the heated products of combustion from passing over the partition-wall of the furnace, and thus passing to the chimney-flue without having passed back and forth beneath the evaporating-pan, and thus escaping without having given their heat to the said pan.

The invention consists in an evaporator constructed with angle-irons attached to the bottom of the pan to prevent the products of combustion from passing between the said pan and the top of the partition-wall of the furnace. Upon the top of the partition-wall is placed a cap having side flanges to overlap the sides of the said wall and a central groove to receive the angle-irons of the pan, as will be herein-after fully described.

A represents the furnace, which is built with a partition-wall, B, extending from the forward end of the furnace nearly to its rear end, as shown in Fig. 1, so that the products of combustion from the combustion-chamber C will pass around the rear end of the wall B through the flue D, and pass into the chimney-flue E at the forward end of the furnace A, as shown in Fig. 1.

F is the evaporating-pan, which rests upon the side and end walls of the furnace A and upon the partition-wall B.

To the bottom of the pan F are riveted or otherwise secured angle-irons G, which can be made of wrought or cast iron, and which may rest against the sides of the top of the wall B, as shown in Fig. 4, or in a longitudinal channel or groove, H, formed in the said top, as shown in Fig. 5. In the former case the irons

G can be hinged at the outer edges of their upper arms, or at the outer ends of rivets, bolts, or arms formed upon or attached to them, to the eyes of rivets attached to the said pan. In the latter case one or two angle-irons G can be used, and when two are used a bar or brick, I, can be placed between them within the said groove.

If desired, a cap, J, can be placed upon the top of the wall B, for the pan to rest upon, which cap can be a tile, as indicated in Fig. 2, or can be made of iron, as may be desired. In either case the cap J should have the groove H along its middle part to receive one or more angle-irons G to prevent the products of combustion from passing over the wall B between the cap J and the bottom of the pan F. Upon the sides of the cap J are formed downwardly-projecting flanges K to overlap the sides of the top of the wall B, and thus make a closer connection between the said cap and wall.

By this improvement a more even heat will be given to the pan and a larger proportion of the heat will be utilized than when a part of the products of combustion are allowed to pass over the top of the partition-wall.

Having thus fully described my invention, I claim as new and desire to secure by Letters Patent—

1. In an evaporator, the combination, with the evaporating-pan F and the partition-wall B of the furnace, of one or more angle-irons, G, substantially as herein shown and described, whereby the products of combustion are kept from passing over the top of the said wall, as set forth.

2. In an evaporator, the combination, with the evaporating-pan F, the partition-wall B, and one or more angle-irons, G, of the cap J, having central groove, H, and side flanges, K, substantially as herein shown and described.

3. In an evaporator, the cap J, made, substantially as herein shown and described, with side flanges, K, and a central groove, H, substantially as herein shown and described, to adapt it to be interposed between the top of the partition-wall and the bottom of the evaporating-pan and to receive the angle-irons attached to the said pan, as set forth.

JOSEPH M. DUNCAN.
